UNITED STATES PATENT OFFICE.

GEORGE S. HILL, OF STRAFFORD, NEW HAMPSHIRE, ASSIGNOR TO UNITED SHOE MACHINERY CORPORATION, OF PATERSON, NEW JERSEY, A CORPORATION OF NEW JERSEY.

BUTTONHOLE-SEWING MACHINE.

Original application filed October 13, 1917, Serial No. 196,418. Divided and this application filed April 10, 1919. Serial No. 283,905.

To all whom it may concern:

Be it known that I, GEORGE S. HILL, a citizen of the United States, residing at Strafford, in the county of Strafford and 5 State of New Hampshire, have invented certain new and useful Improvements in Buttonhole-Sewing Machines; and I do hereby declare the following to be a full, clear, and 10 exact description of the invention, such as will enable others skilled in the art to which it appertains to make and use the same.

The invention relates to stitch forming mechanism for sewing overseams and more particularly to mechanisms comprising an 15 upper needle, a looper which takes a loop of upper needle thread below the work, and an under needle which carries a loop of its thread up through the loop held by the looper and into position above the work for 20 the passage down therethrough of the upper needle.

One feature of the invention contributes 25 to the speed and accuracy with which the parts of the stitch forming mechanism may be operated. This feature contemplates actuating the upper and under needles of the sewing mechanism from two cranks on the sewing shaft, one of which is connected to 30 transmit a simple harmonic motion to the upper needle bar, while the other is connected with the mechanism which oscillates and dips the under needle through pivotally supported connections which transmit to the under needle the differential movements 35 requisite for properly and accurately timing it with relation to the upper needle. This actuating mechanism may be run at high speed without material wear or strain on the parts, while ensuring the proper co-operation 40 of the needles and looper in the stitch forming cycles.

Further features relate to the manner of mounting the rotary head which carries the upper needle bar and to the means for controlling the thread at certain points in the 45 stitch forming cycle.

The invention will be readily understood 50 from the inspection of the accompanying drawings and the following detailed description of the mechanism illustrated therein.

In the drawings, Fig. 1 is a front elevation of a buttonhole sewing machine em-

bodying the invention in its preferred form, and Fig. 2 is a detailed side elevation showing the thread controlling the mechanism.

This application is a division of application 196,418 filed October 13, 1917, which shows and describes the machine in which the invention has been embodied. The machine comprises in general a cutter for cutting the buttonhole slit, a work clamp which is movable lengthwise and laterally of the buttonhole, and a stitch forming mechanism which is rotated during the sewing about 65 the eye and about the bar end of the buttonhole.

The stitch forming mechanism comprises a straight eye-pointed upper needle 2 which is arranged to penetrate the work a short 70 distance from the edge of the buttonhole slit, a curved eye-pointed under needle 4 which is arranged to pass up through the buttonhole slit and which at the upper end of its stroke is dipped to throw out a loop 75 down through which the upper needle passes, and a looper 6 arranged below the work and operating to take a loop of upper needle thread and to carry it into such position that the under needle will pass up 80 through it during its up stroke. The upper needle is secured in the lower end of a hollow needle bar 8 which is mounted to reciprocate through and turn with a rotary head 10. The needle bar is reciprocated by a 85 crank 12 carried on the forward end of the sewing shaft 14 and connected by a link 16 with a sleeve 18 held between collars on the bar. The pivot pin 20 for the lower end of the link projects beyond the rear face of the 90 link and engages a bearing block arranged to reciprocate in a guideway 22 formed in the machine head, and acting to guide and steady the upper end of the needle bar.

The under needle is mounted upon a rotary turret 24 and is actuated by a second crank 26 formed on the sewing shaft and engaging one end of a lever 28 supported intermediate its ends upon a swinging fulcrum pin 30 projecting from an arm 32 pivoted on a stud 34. The outer end of the lever is connected by a link 36 with an arm 38 secured to one end of a rock shaft 40. An arm 42 is secured to the other end of the rock shaft 40 and is connected by a ball and 100 socket joint with the lower end of a hollow

link 44, the upper end of which is connected to an arm projecting from a rock sleeve 46 on the turret. The rock sleeve is provided with a vertical arm 48 which is connected by a link 50 with the swinging carrier 52 in which the upper needle is mounted. The arm 48 and link 50 are so arranged that the pivotal connection between them passes the line of centers at the end of the upward stroke of the under needle, so that the needle is dipped to form a loop for the passage therethrough of the upper needle.

The swinging arm 32 on which the crank lever 28 is fulcrumed is so arranged and the parts are so proportioned that during the first part of the revolution of the sewing shaft from the stopped position indicated in the drawings the fulcrum 30 will swing upward as the crank 26 moves downward, thus giving a rapid movement to the end of the crank lever which is connected by the link 36 with the under needle mechanism. The under needle is therefore quickly advanced to its upper position and dipped while the upper needle is starting its downward stroke, while the return stroke of the under needle is delayed until the upper needle has passed through the loop of under needle thread and has penetrated the work. The looper 6 is constructed and arranged like the looper of Patent No. 1,134,046, dated March 30, 1915, and is operated from the rock sleeve 46 in a similar manner.

By properly proportioning the crank lever and swinging fulcrum arm 32, and properly arranging the arm, the movements of the under needle and looper may be accurately timed with relation to the movements of the upper needle when reciprocated by a simple crank movement, and the sewing mechanism may be driven at high speed without strain or material wear upon the parts.

The rotary head 10 in which the upper needle bar is mounted is in the form of a sleeve projecting above and below the gear 54, which may be formed upon or secured to the sleeve in any suitable way, and is connected with the mechanism for rotating the stitch forming mechanism. The lower part of the sleeve is fitted to turn in the bearing in the head of the machine while the upper part of the sleeve is fitted to turn in a bearing block 56. The bearing block 55 is provided with grooves on its side which engage short ribs 58 formed on the head of the machine. The head is recessed above the ribs so that the bearing block may be slid vertically into position between the ribs and then secured by the screws 60. This construction provides an adequate bearing for the needle bar so that a short light bar may be used, and also efficiently supports the rotary head or sleeve by bearings arranged both above and below the point at

which the actuating means through which the sleeve is rotated is connected with the sleeve.

The upper needle thread leads from a thread supply through the holes of a guide strip 62 between the discs of a tension 64, through guides 66, 68, over pin 70, and under the vertically adjustable guide finger 72, from which it passes to the upper end of the hollow needle bar. The thread passes down through the needle bar through an opening at the lower end of the bar, and thence through suitable guides or light tension devices to the eye of the needle. During the sewing the thread is acted upon by a thread controller 74 carried by the link 16 and arranged to pass out between the guides 66 and 68, and to take up slack in the upper needle thread when the looper releases the loop taken by it during previous reciprocation of the needle.

While it is preferred to employ the specific construction and arrangement of parts shown and described, particularly in embodying the invention in the machine of the application above referred to, it will be understood that this construction and arrangement is not essential to the broader features of the invention, and may be varied or modified as found desirable or best suited to the construction of the machine in which the invention is to be embodied.

What is claimed is:

1. A buttonhole sewing machine having, in combination, stitch forming mechanism comprising a vertically reciprocating upper needle bar and an oscillating under needle and looper, mechanism for oscillating and dipping the under needle, a crank for reciprocating the upper needle bar, a crank for operating the under needle, a crank lever, a shifting fulcrum for the lever, and connections from the end of the lever to the mechanism for oscillating and dipping the under needle.

2. A buttonhole sewing machine having, in combination, stitch forming mechanism comprising a vertically reciprocating upper needle bar, a crank connected to transmit a substantially simple harmonic movement thereto, an under needle, mechanism for oscillating the under needle and dipping it at the upper end of its stroke, a crank lever having one end connected to said mechanism, a crank engaging the other end of the lever, and a shiftable fulcrum for the lever.

3. A buttonhole sewing machine having, in combination, stitch forming mechanism comprising a vertically reciprocating upper needle bar, a crank connected to transmit a substantially simple harmonic movement thereto, an under needle, mechanism for oscillating the under needle and dipping it at the upper end of its stroke, a crank lever having one end connected to said mechanism,

a crank engaging the other end of the lever, and a pivoted arm on which the lever is fulcrumed.

4. A buttonhole sewing machine having, 5 in combination, stitch forming mechanism comprising a vertically reciprocating upper needle bar and an under needle and looper, a sewing shaft, two cranks on the shaft, a link connecting one crank to the upper 10 needle bar, mechanism for oscillating and dipping the under needle and operating the looper, a lever having one end engaged by the other crank and the other end connected to the oscillating and dipping mechanisms, 15 and a pivoted arm on which the lever is fulcrumed.

5. A buttonhole sewing machine having, 20 in combination, stitch forming mechanism comprising a reciprocating upper needle bar and an under needle and looper, a crank, a link connecting the crank and bar, a second crank, a lever one end of which is engaged by the latter crank, connections between the 25 other end of the lever and the under needle and looper, and a pivoted arm on which the lever is fulcrumed.

6. A buttonhole sewing machine having, 30 in combination, stitch forming mechanism comprising upper and under needles and a looper which holds a loop of upper needle thread below the work, a crank for reciprocating the upper needle, stationary thread guides, a thread controller operated by the crank and playing between the guides to

control the upper thread when released by 35 the looper during the downward stroke of the needle.

7. A buttonhole sewing machine having, 40 in combination, stitch forming mechanism comprising upper and under needles and a looper, stationary thread guides at one side of the upper needle bar, mechanism for reciprocating the bar, and a thread controller given an orbital movement between the 45 guides by the bar-actuating mechanism to control the upper thread when released by the looper.

8. A buttonhole sewing machine having, 50 in combination, stitch forming mechanism comprising upper and under needles and a looper, a crank for reciprocating the upper needle, a link connecting the crank to the upper needle bar, stationary thread guides at one side of the link, and a thread controller carried by the link and playing between the guides.

9. A buttonhole sewing machine having, 55 in combination, a vertically reciprocating upper needle bar, complementary under mechanism, a rotary sleeve in which the bar 60 is mounted, a fixed bearing for the lower part of the sleeve, a bearing block for the upper end of the sleeve, vertical positioning ribs engaging slots in the sides of the block, means for securing the block in position, 65 and a gear on the sleeve between the bearings.

GEORGE S. HILL.
